DRESSER OR THE LIKE

Huey T. Keller, 1609 Davidson Road,
High Point, N.C. 27260

Continuation-in-part of design application Ser. No. 24,400,
Aug. 10, 1970. This application Oct. 2, 1972, Ser. No.
296,942

Term of patent 14 years

Int. Cl. D6—04

U.S. Cl. D6—154

FIG. 1

2
74

FIG. 3

FIG. 1 is a top plan view of the dresser or the like, showing my new design;

FIG. 2 is a front elevational view of the same, the rear being substantially plain and unornamented; and

FIG. 3 is an end elevational view of such design, the opposite end being substantially a mirror image thereof.

This is a continuation-in-part of design application Ser. No. D. 24,400, filed Aug. 10, 1970.

I claim:

The ornamental design for a dresser or the like, as shown and described.
